UNITED STATES PATENT OFFICE.

CAMPBELL P. HIGGINS, OF BROOKLYN, NEW YORK.

DIE FOR CORRUGATING BARS OR TUBES.

SPECIFICATION forming part of Letters Patent No. 364,349, dated June 7, 1887.

Application filed December 7, 1886. Serial No. 220,925. (No model.)

To all whom it may concern:

Be it known that I, CAMPBELL P. HIGGINS, a citizen of the United States, residing at Brooklyn, New York, have invented a new and useful Improvement in Forming Corrugated Tubes or Bars, of which the following is a specification, reference being had to the accompanying drawings, in which—

Figure 1 is a central vertical longitudinal section on the line $x\bar{x}$, Fig. 2, of a pair of dies in their closed position; Fig. 2, a vertical transverse section of the same on the line $x'\bar{x}'$, Fig. 1; Fig. 3, a partial longitudinal section similar to Fig. 1, but showing the dies in their open position; and Fig. 4, a transverse section in the same plane as Fig. 2, the position corresponding with Fig. 3. Fig. 5 is a vertical transverse section of Fig. 1 on the line $x^2\bar{x}^2$. Fig. 6 is a partial plan view of the upper die-trough, D; Fig. 7, a partial exterior elevation of one of the sections of the lower die; Fig. 8, an end view of both sections of the lower die; Fig. 9, a plan view of Fig. 7; Fig. 10, a partial interior elevation of one of the upper die-sections, and Fig. 11 an inverted plan view of Fig. 10.

Similar letters of reference indicate corresponding parts in the several figures.

This invention relates to improvements in machinery for forming from malleable iron tubes of rectangular shape in cross-section corrugated headers for use in sectional steam-boilers, said invention being adaptable, also, to corrugating solid rectangular bars; and in order that others may understand and use the same, I will proceed to describe the details of its construction, explain its operation, and subsequently point out in the appended claims its novel characteristics.

Referring to the drawings, A A' and B B' are dies or formers having interior working-surfaces which present together a rectangular shape in cross-section and are capable of both vertical and lateral contraction. The vertically-acting faces are of serpentine form longitudinally, the several projecting curvatures of either set of dies corresponding in position with depressed curvatures in the counterpart faces of the opposite set. The lateral vertical faces present plane surfaces throughout the length of the interior, and are composed of interlocking plates or tongues which approxi-

mate in width to each unit of corrugation and project alternately from the upper and lower sets of dies—viz., 1, 2, 3, 4, 5 from the upper set and 6, 7, 8, 9 from the lower set of said dies.

The lateral contractile movement of the dies is acquired by their vertical longitudinal subdivision into equal sections or pairs, the several inclined webs $a\bar{a}'\bar{b}'$ of which engage with the converging interior surfaces of the trough-like abutments D E and cause a compression of the halves of the dies toward one another in a direction at right angles to the motion of the abutments during the act of corrugation.

The sections A and A', B and B', of the upper and lower dies are retained in their proper coinciding relations to one another by means of the bolts $e\bar{e}$ and $f\bar{f}$, respectively, the heads of which are contained in countersunk sockets, as shown in Fig. 5, which are sufficiently countersunk to allow a separation of the sections to the extent shown in Fig. 4 at the time when the dies are separated. Similar bolts, g , Fig. 4, are employed to suspend the upper die-sections in the abutment D; but the same have also a transverse elongation of their sockets in the said abutment (shown by Fig. 6) provided in order to permit the lateral movement of the said sections. In the present instance the lower die-sections are in turn suspended to the upper die-sections by means of bolts or bars c , which project through vertical slots c' , formed in several of the inclined webs $a\bar{a}'\bar{b}'$, said slots being of sufficient combined vertical length to permit the necessary motion of the dies, the bolts c being retained in place by spring-pins c^2 . However, the sections B B' may be connected independently to the abutment E by bolts similar to the bolts g of the sections A A'; and incident to this construction the lower pair of dies may be provided with suitable springs interposed beneath between them and the abutment E, to serve the purpose of lifting and releasing them from lateral compression between the inclines of said abutment E when it is desired to insert or remove the work. The said springs are not illustrated herewith, being of any well-known form—as, for instance, spiral—and coiled about the said bolts corresponding with the bolts g or substituted in place of the same.

In the operation of the invention the abutments D and E are secured upon the heads of a hydraulic or other suitable press, which on opening separates them. A blank of straight pipe having a square or, in the present instance, a rectangular cross-section is introduced in a heated condition and a suitable mandrel inserted within the blank, preferably one of a construction which I have described for the purpose in a separate application filed June 24, 1886, No. 206,103, said mandrel being expanded laterally within the blank, so as to firmly press against the vertical sides of the interior. By the closing movement of the press the abutments D and E are made to approach, and as the work comes in contact with the acting serpentine faces *h i* of the dies the latter are forced between the converging faces of the abutments, and by reason of the wedging action of the inclined webs *a a' b b'* are compressed laterally simultaneously with their vertical compression upon the exterior of the work.

The action of wedging the interior sectional mandrel employed in this operation outwardly against the vertical sides of the blank and wedging the interlocking sectional sides or tongues 1 2 3, &c., of the dies inwardly, so as to bear solidly upon the exterior, clamps the metal firmly between the two surfaces, and prevents the same from buckling when the operation of pressing into corrugations is performed, the said sectional surfaces corresponding with each unit of corrugation and moving alternately in unison with one another, thereby carrying the adjacent portions of the metal supported by and gripped between them in directions corresponding to the movements of the corrugations.

Having thus fully described my invention, what I claim, and desire to secure by Letters Patent, is—

1. The combination of upper and lower die-carriers having exterior surfaces inclined to-

ward each other at a point where pressure is transmitted, with sectional dies having the exterior surfaces similarly inclined, whereby the motion of the die-carriers shall close the sections of the dies together at right angles to the motion of the die-carriers previous to the closing of the dies.

2. The combination of die-carriers having inclined surfaces with a set of sectional dies capable of movement in two directions, substantially as specified.

3. Corrugating dies having a series of interlocking tongues, said tongues approximating in width to a unit of the corrugation, and adapted to move with the surface of the metal being corrugated.

4. Corrugating dies having the working sides formed of a series of interlocking tongues, said tongues approximating in width to a unit of the corrugation, and adapted to approach each other and to move with and in the same direction of the surface of the metal being corrugated.

5. In corrugating dies, the combination of the following elements: first, dies provided with interlocking tongues having exterior inclined planes and adapted to clamp the sides of the article to be corrugated and to move therewith; second, trough-shaped carriers adapted to fit the exterior of said interlocking tongues or dies.

6. In corrugating dies, the combination of the following elements: first, dies comprising interlocking tongues having exterior inclined surfaces and adapted to clamp the surfaces of the blank which they inclose; second, trough-shaped carriers adapted to fit the exterior of said interlocking tongues or dies, and, third, means, as loose-fitting bolts, for connecting the dies with the carriers.

CAMPBELL P. HIGGINS.
